JOHN P. CLULEY, OF CHICAGO, ILLINOIS.

METHOD AND MEANS FOR STRIPPING FIBROUS PLANTS.

1,134,514.

Specification of Letters Patent. Patented Apr. 6, 1915.

Application filed May 22, 1911. Serial No. 628,882.

To all whom it may concern:

Be it known that I, JOHN P. CLULEY, a citizen of the United States, residing at Chicago, in the county of Cook and State of Illinois, have invented new and useful Improvements in Methods and Means for Stripping Fibrous Plants, of which the following is a specification.

Heretofore the shive or woody pith of flax, hemp and other fibrous plants has been removed by crushing and hackling the stalks but this has involved breaking the fiber to a considerable extent and thereby lessening its value. It is desirable to pre-serve the fiber in its full length but the methods of removing the shive heretofore practised have invariably involved breaking and dividing the fiber to a very considerable extent into irregular lengths.

The object of this invention is to loosen the shive from the fiber of fibrous plants and to remove the greater portion, if not the whole, of the shive without injury to the fiber.

With these ends in view my invention contemplates first crushing the stalks in the sense of flattening them, and then causing the flattened stalks to travel in a tortuous path over bending rolls, thereby bending the flattened stalks alternately in opposite directions but without scraping or fracturing the fiber. The flattening operation serves to prepare the stalk for the bending operation by flattening the tubular structure of the stalk and the bending operation breaks the shive into short lengths and separates it from the fiber. Owing to the delicacy of the fiber it may be that there will be some slight fracture thereof in the several operations, and, hence for clearness of disclosure I desire to have it understood that when I say the shive is removed without injuring the fiber I mean that the fiber is uninjured in the commercial rather than the strict literal sense. While the greater portion of the shive will be entirely removed from the fiber during these operations some pieces may remain engaged or entangled with the fiber but these will comprise a very small proportion of the whole and they will be removed in handling the fiber or by shaking it.

In the accompanying drawings illustrating a machine which may be employed for practising my invention Figure 1 is a side elevation; Fig. 2 is a longitudinal central sectional view; Fig. 3 is a top plan view with

the upper carrier belt broken away to disclose the bending rolls; Fig. 4 is a transverse sectional view on the line 4—4 of Fig. 3, and Fig. 5 is a detail diagrammatic view showing the arrangement of the bending rolls and the position of the carrier belts.

Referring to the drawings in which like numerals of reference denote corresponding parts in the several figures, 6 designates a frame and 7 and 8 two belt conveyers which are trained on the receiving rolls 9, discharge rolls 10 and bending rolls 11. The receiving and discharge rolls are mounted on shafts 9', 10', which are journaled in the sides of the frame. Sprocket wheels 12 and 13 are mounted on the lower shafts 9', 10', at one side of the frame, and a sprocket chain 14 is trained on said sprocket wheels. At the other side of the frame the two shafts 75 9' carry intermeshing gears 15 and the two shafts 10' carry intermeshing gears 16 so that all of the rolls 9 and 10 will travel at the same rate of speed and move the belt conveyers at the same rate of speed also. 80 One of the roll shafts, preferably the lower shaft 9', carries a belt pulley 17 whereby power is applied to the machine.

The bending rolls 11 are arranged in staggered relation between the receiving and discharge rolls and preferably adjacent to the discharge rolls for a reason hereafter described. One of these rolls, preferably the intermediate roll 11', is mounted at its ends in bearing blocks 18 which are guided 90 in openings 19 in the side of the frame. These blocks and the roll 11' are adjustable vertically to take up slack in the conveyers, and adjust the tension thereof. The blocks are carried by vertical rods 20 which are guided in brackets 21 on the sides of the frame and have their upper ends screw-threaded to receive the nuts 22 arranged to bear on the brackets. By adjusting the nuts the roll 11' can be moved up or down to adjust the conveyer belts to the proper tension.

A pair of flattening rolls 23 is arranged in front of the receiving rolls, and the lower flattening roll is preferably made adjustable 105 relative to the upper flattening roll. The upper flattening roll is mounted on a shaft 23' which is journaled in the sides of the frame and carries a gear 24 on one end which meshes with an idle gear 25 in turn meshing with a gear 26 on the upper receiving roll shaft 9' (Fig. 1). The lower flat-

tening roll is mounted upon a shaft 27, the ends of which are supported on yielding bearings 28 at the sides of the frame. This shaft 27 carries a gear 29 which meshes with 5 the gear 24 so that both crushing rolls will travel at the same rate of speed.

The receiving rolls 9 are separated from each other, as shown in Fig. 2, so that the conveyer belts will not come in contact until 10 they approach the first bending roll and the distance between the flattening rolls and the point where the stalks will be gripped by the conveyer belts is greater than the length of the stalk. The receiving, discharge and 15 bending rolls are geared to travel at a higher rate of speed than the flattening rolls. The conveyer belts engage the stalks as they come from the flattening rolls and exert sufficient pull on the stalks while still 20 engaged by the flattening rolls to straighten the stalks without breaking them because, as before stated, the gripping point of the conveyer belts is at a greater distance from the flattening rolls than the length of the 25 stalks. Thus I provide for straightening the stalks before they are subjected to the bending operation and this straightening is accomplished without manual manipulation and without injury to the stalks.

30 The machine which I have described embodies the essential elements for practising my improved method but it will be understood that the form, proportion and particular arrangement of parts may be varied 35 in many ways without departing from the spirit or sacrificing the advantages of the invention.

In practice the stalks are fed to the flattening rolls and they pass between these 40 rolls and in between the conveyer belts. The latter engage the stalks sufficiently to pull them into a straight position lengthwise of the machine but without gripping the stalks and without exerting sufficient force to 45 break or injure the stalks which are still gripped by the flattening rolls. In their passage between the flattening rolls the tubular structure of the stalks is crushed sufficiently to flatten them and this prepares 50 the stalks to stand the reverse bending operations to break up and separate the shive without injury to the fiber. As the stalks are carried by the conveyer belts around the bending rolls they are alternately bent in 55 opposite directions a plurality of times and this bending is sufficient to break the dry and brittle shive without in any way injuring the fiber because there is no lengthwise or other strain on the fiber sufficient to break 60 it and also because the stalks have been previously prepared in the flattening operation. The stalks are not subjected to any scraping action as they pass through the machine, which would have a tendency to break the 65 fiber. The number of bending rolls may

be varied as found desirable but it is now believed that the best results will be obtained with five rolls arranged in or about the manner shown in the drawings. During the bending operation the shive is not only 70 broken and separated from the fiber but this separation is usually sufficient to wholly disconnect the broken shive from the fiber so that it will drop away from the fiber after the treated stalks leave the conveyer at the 75 discharge rolls. But if any of the broken shive remains intermingled with the fiber after being discharged from the machine it will be readily separated therefrom in handling or by shaking bundles of the fiber. 80

In Fig. 5 of the drawing I have shown diagrammatically the two conveyer belts 7, 8 and the material 30 passing therethrough. It will be noted that the bending operation to which the stalks are subjected is distinctly different from the operation to which they would be subjected between intermeshing corrugated rolls. In the latter case the stalks are bent at the apex of each corrugation in opposite directions at a distinct angle the same as if a stalk is bent over a sharp edge or by grasping it with the two hands and then bending it. The result of such an operation is to stretch and break the fiber to an extent depending upon the angularity of the bend and this is the general method which has been practised commercially heretofore. My bending operation does not contemplate such an angular bend of the stalks but on the contrary it simply 90 involves propelling the stalks under constant and equal pressure in opposite directions over a plurality of curved surfaces arranged in staggered relation so that at no time is there sufficient strain or stretching 95 of the fiber to produce fracture. This alternate bending of the stalks in opposite directions under pressure breaks the brittle shive from which the fiber has been loosened but does not injure the fiber. 100

110 It is important that the stalks should not be gripped by the conveyer belts before they leave the flattening rolls for this might break the stalks. But with the arrangement illustrated in the drawings whereby the conveyer belts exercise a pulling action on the stalks, without gripping them, while the stalks are still gripped by the flattening rolls I provide for straightening the stalks before they are subjected to the bending operation. The stalks are carried by the conveyer belts in a tortuous path under pressure without pulling them lengthwise and this effectually divides the shive into small sections without injury to the fiber. The 120 flattening rolls also serve to remove the seeds from the stalks. Thus I provide a simple method and means for stripping the fiber from the stalks of fibrous plants, particularly flax and hemp, without injury to 125 130

the fiber, and, as before stated, this is especially important commercially because it is desirable to preserve the full length of the fiber.

5 I claim:

1. In a machine for treating the stalks of fibrous plants to separate and remove the shive or woody pith from the fiber without injuring the fiber, the combination of a pair 10 of crushing rolls to flatten the stalks, a pair of conveyer belts to receive and carry the flattened stalks therebetween, a plurality of bending rolls arranged in staggered position and adjacent relation over which the 15 stalks travel, said belts being arranged to engage the stalks as they emerge from between the flattening rolls but not to grip the stalks until after they have left the flattening rolls, and means for operating said belts 20 at a higher rate of speed than the flattening rolls.

2. In a machine for treating the stalks of fibrous plants to separate and remove the shive or woody pith from the fiber without 25 injuring the fiber, the combination of a pair of crushing rolls to flatten the stalks, one of said rolls being mounted to yield relative to the other roll, a pair of conveyer belts arranged to receive and carry the stalks 30 therebetween, a plurality of bending rolls arranged in staggered position and adjacent relation over which the belts travel in a tortuous path, said belts being separated from each other adjacent to the flattening rolls to 35 engage the stalks while still gripped by the flattening rolls and exert a gentle pull thereon to straighten the stalks and said belts coming together to grip the stalks as they approach the first flattening roll over which 40 they travel with the belts.

3. In a machine for treating the stalks of fibrous plants to separate and remove the shive or woody pith from the fiber without 45 injuring the fiber, the combination of a pair of crushing rolls adapted to flatten the stalks, a pair of belts, a plurality of bending rolls over which said belts are arranged to travel in unison to bend the stalks, a pair of guiding rolls spaced apart over which

said belts travel, said guiding rolls being 50 arranged to separate the said belts adjacent the crushing rolls so that the said belts will engage the flattened stalks at their ends and draw them into straight parallel relation before the said stalks reach the bending 55 rolls and become firmly grasped by the rolls.

4. In a machine for treating the stalks of fibrous plants to separate and remove the shive or woody pith from the fiber without 60 injuring the fiber, the combination of a pair of crushing rolls adapted to flatten the stalks, a pair of belts, a plurality of bending rolls over which said belts are arranged to travel in unison to bend the stalks, a pair of guiding rolls spaced apart over which said 65 belts travel, said guiding rolls being arranged to separate the said belts adjacent the crushing rolls so that the said belts will coact with the crushing rolls by grasping the flattened stalks at their ends while the 70 said stalks are still engaged with the crushing rolls to straighten the same and arrange them in parallel relation before they reach the bending rolls.

5. The hereindescribed method of stripping stalks of fibrous plants to separate and remove the shive or woody pith from the fiber without injuring the fiber which consists in subjecting the stalks to a flattening operation without bending the stalks, loosely 80 engaging one end of each of the stalks while the other end is still undergoing the flattening operation, gradually gripping said loosely engaged ends and subjecting said stalks to an increasing tension whereby the 85 stalks are straightened, arranging the stalks in separate parallel relation to each other, breaking the flattened pith by alternately bending the stalks continuously in both directions from their normal longitudinal 90 axes, the bends being circular arcs of sufficient radius to prevent breaking of the fiber.
